Patented Dec. 31, 1901.

J. WIESER.

PNEUMATIC VALVE ACTION.

(Application filed Apr. 18, 1901.)

(No Model.)

UNITED STATES PATENT OFFICE.

JOSEPH WIESER, OF BROOKLYN, NEW YORK, ASSIGNOR OF ONE-HALF TO
KARL FINK, OF NEW YORK, N. Y.

PNEUMATIC VALVE-ACTION.

SPECIFICATION forming part of Letters Patent No. 690,381, dated December 31, 1901.

Application filed April 13, 1901. Serial No. 55,642. (No model.)

To all whom it may concern:

Be it known that I, JOSEPH WIESER, a citizen of the United States, residing in New York, borough of Brooklyn, in the State of New York, 5 have invented certain new and useful Improvements in Pneumatic Valve-Actions, of which the following is a specification.

My invention relates to pneumatic valve-actions for mechanical musical instruments—
10 such as pianos, organs, and the like—especially for self-playing or automatic pianos, in which the pneumatic valve-action is under the control of a perforated music-sheet.

The main object of the present invention 15 is to provide a pneumatic valve-action which will respond instantly when a perforation in the music-sheet is open to one of the passages of the tracker, so that the piano, organ, or other instrument will be played in proper time without any hesitation.

A further object is to render the mechanism more compact.

My invention consists of a pneumatic valve-action comprising the combination, with the 20 main valves controlling the actuating-pneumatics, of auxiliary valves and means for actuating the main and auxiliary valves, such means comprising tracker-passages leading, on the one hand, to the diaphragms of the 25 auxiliary valves and, on the other hand, to the diaphragms of the main valves, whereby when atmospheric air is permitted to pass through the perforation of the music-sheet and through the tracker and tracker-tubes 30 the automatic auxiliary valves will instantly shut off the flexible diaphragms of the main valves from the lower suction influence, allowing the flexible diaphragms of the main valves to rise and to thereby instantly open 35 the main valves, so that the pneumatics will instantly operate on the actuating mechanism of the piano or other instrument, all as hereinafter described and then claimed.

In the accompanying drawings, Figure 1 is 40 a vertical transverse section through the valve-chest and a pneumatic, the parts being in normal position and connected with a piano-action; and Fig. 2 is a vertical longitudinal section of the valve-chest and its contained

parts, showing one set of valves and the corresponding pneumatics in actuated position.

Referring to the drawings, A indicates a valve-chest, which is constructed of suitable parts, so as to provide longitudinal suction-channels B B' B², which are all in communication with the main suction-pipe C, which leads to the suction or exhaust chest. (Not shown.) Above the said suction-channels B B' B² is arranged a series of valve-chambers B⁴, which lead, by means of ports d, to the pneumatics D, that are fixed in any suitable manner on top of the valve-chest A. These pneumatics are connected either directly with the valves of the sounding-tubes in case the device is used in connection with an organ, or each pneumatic may be connected with a lever E by means of a link e, which lever is pivoted at e' to a rail E and is connected at one end by means of a link E² with the piano-action x.

In the valve-chambers B⁴ are arranged a number of flap-valves F, which control the ports f that connect the channel B with the valve-chambers B⁴, and which main flap-valves F are preferably provided with lugs or projections f' at the back, upon which rest the 75 free ends of the contiguous flap-valves F', that control the ports f², arranged under the pneumatics, and which lead to the outer air. Normally the two valves F F' are in the position shown in Fig. 1, in which position port f is 80 closed and the port f² is open, so that atmospheric air may pass through the said port f² and fill the pneumatic D controlled thereby. The ports f are crossed by suitable guide-pieces f³, in which are guided the stems g of heads g', which rest upon the flexible diaphragms G, the edges of which are glued or otherwise fastened in the well-known manner in the suction-channel B.

Arranged below the diaphragms G in the 90 suction-channel B' and communicating with the undersides of the said flexible diaphragms by means of ducts i are a number of auxiliary automatic or flap valves H, which are normally open, so that the ducts i will permit the 95 diaphragms G to be subjected to the suction of the channel B'. These auxiliary automatic valves H rest upon stems h, which are guided

in the stock of the valve-chest or in any other suitable manner between the channels $B' B^2$. Each of said valve-stems h has coiled around it an actuating-spring h' , which bears upon 5 the head h^2 of the valve-stem at one end and against the stock of the valve-chest at the other end. Each head h^2 rests upon a flexible diaphragm h^3 , said diaphragms h^3 being arranged within the suction-channel B^2 and 10 being subjected to suction at their under sides through the medium of ducts j , which communicate by means of ports j' with a suction-channel B^3 in the valve-chest. The ports j' are opened more or less by means of needle- 15 valves J for regulating the escape of air through the suction-channel B^3 and to retard or expedite the return of the diaphragms h^3 into normal position after the pneumatic valve-action has been operated. The ducts 20 $i j$ are paired, as it were, and are connected by means of branch passages $k k'$, which communicate with the tracker-tubes that lead in the usual manner to the tracker, over which a 25 perforated music-sheet passes in the well-known manner.

The operation of my improved pneumatic valve-action is as follows: The suction-channels in the valve-chests are subjected to exhaust or suction in the well-known manner 30 and the perforated music-sheet operated. Whenever a perforation in the music-sheet establishes communication between one of the tracker-tubes K and the outer air, the atmospheric air enters the branch passages $k k'$ beneath the diaphragm h^3 and, against the exhaust or suction on the upper side of the diaphragm, throws up the diaphragm into opposite direction, as shown in Fig. 2, causing the same to act upon the valve-stem head h^2 and 35 to close the valve H , so that the duct i has no communication with the suction-channel B' . As soon as the valve H is closed, according to the operation previously described, the atmospheric pressure admitted through the passage k is fully effective to raise the diaphragm G , causing the main valve F to be raised, so 40 as to open the port d of the pneumatic to the suction-chamber B , thereby permitting atmospheric pressure to deflate the pneumatic 45 D , which in turn instantly actuates the sounding devices. The atmospheric air being shut off from the tracker-tube K , the suction through the ports j' will create an equilibrium above and below the diaphragm h^3 , causing 50 the automatic valves H and diaphragms to 55 return to normal position.

By operating the main valves of a pneumatic valve-action by means of the auxiliary automatic valves, arranged and operating as

described, the main valves are enabled to be 60 instantly opened and closed, thereby greatly improving devices of this class.

What I claim as new is—

1. In a pneumatic valve-action, the combination, with the main valves controlling the 65 actuating-pneumatics, of auxiliary valves, and means for actuating the main and auxiliary valves, such means comprising tracker-passages, leading on the one hand to the diaphragms of the auxiliary valves, and on the 70 other hand to the diaphragms of the main valves, substantially as set forth.

2. In a pneumatic valve-action, the combination, of a valve-chest, provided with a plurality of suction-channels extending therethrough, valve-chambers, main valves arranged in said valve-chambers and adapted to control the actuation of the pneumatics, and flexible diaphragms arranged in one of said suction-channels, for opening the main 80 valves, of auxiliary valves arranged in another of said suction-channels, flexible diaphragms arranged in still another of said suction-channels, for actuating the auxiliary valves, and tracker or atmospheric-air passages, leading on the one hand to the under 85 sides of the flexible diaphragms of the main valves and directly to the said auxiliary valves, and on the other hand to the diaphragms of the auxiliary valves, substantially 90 as set forth.

3. In a pneumatic valve-action, the combination, with a valve-chest, provided with a plurality of suction-channels extending therethrough, valve-chambers, main valves arranged in the valve-chambers and controlling the suction to the pneumatics, flexible diaphragms arranged in the uppermost of said channels, and means acted on by said diaphragms for actuating the main valves, of auxiliary valves arranged in the next following suction-channel, flexible diaphragms arranged in the next suction-channel, and adapted to actuate the auxiliary valves, and tracker or atmospheric-air passages, leading 105 on the one hand to the undersides of the flexible diaphragms of the main valves and to the auxiliary valves, and on the other hand to the diaphragms of the auxiliary valves, substantially as set forth.

In testimony that I claim the foregoing as my invention I have signed my name in presence of two subscribing witnesses.

JOSEPH WIESER.
